(57) **CLAIM**

The ornamental design for a chair armrest, as shown and described.

DESCRIPTION

FIG. 1 is a perspective view from above and to one side of a variant of the new design for a chair armrest;
FIG. 2 is a front elevation view thereof;
FIG. 3 is a rear side elevation view thereof;
FIG. 4 is a left side elevation view thereof;
FIG. 5 is a right side elevation view thereof; and,
FIG. 6 is a bottom plan view thereof.

In the drawings, the broken lines depict environmental subject matter only and form no part of the claimed design.
